UNITED STATES PATENT OFFICE

2,547,296

VERTICALLY ADJUSTABLE TABLE

James E. White, Los Angeles, Calif.

Application May 17, 1948, Serial No. 27,391

4 Claims. (Cl. 311—39)

1

This invention has to do generally with improvements in tables, and is directed particularly to various features of construction and adjustability rendering the invention especially suitable for school or classroom tables, as well as other places where high strength and rigidity, along with adjustability, are required under conditions of hard usage.

One of my primary objects is to provide an improved construction whereby the table top is adjustable to different elevations, by telescopic end or leg assemblies, so built as to be capable of supporting all vertical loads, and resisting lateral forces without impairment of the initial strength and rigidity of the assemblies. Briefly, this object is accomplished by forming the end assemblies of vertically telescopic sheet metal sections, strengthened and guided in their telescopic relation by one or more interfitting rib and recess configurations. Preferably, each supporting end assembly is made to comprise upper and lower sheet metal sections, the frame of which is attached to the top structure of the table, while the lower section is attached or applied to a pair of legs with respect to which the top structure is adjustable.

The invention further contemplates an improved end bracket construction and arrangement for attachment of the upper sheet panel section to the table top, the bracket further being adaptable for connection with a beam underlying and extending longitudinally of the table top. As will appear, the invention may advantageously employ a channel form beam, so arranged as to be attached to either or both the end bracket plates and upper telescopic panel section.

All the above mentioned features of the invention, as well as additional objects and the details of a typical and illustrative embodiment, will be understood most clearly and readily from the following detailed description of the accompanying drawing, in which:

Fig. 1 is a perspective view of the table; a portion of the top being broken away to show the end construction;

Fig. 2 is an enlarged fragmentary section taken in the longitudinal vertical center plane of the table, as indicated by line 2—2 of Fig. 3; and

Fig. 3 is a fragmentary section taken on line 3—3 of Fig. 2.

Referring first to the general showing of Fig. 1, the table is shown to be of a flat top design adaptable typically for classroom use and for the accommodation of at least two users or students at one side of the table. The latter may be con-

2

sidered generally as comprising a flat top 10 carried by the end supporting assemblies 11 which, as previously indicated, are characterized by their capacity for vertical adjustment, and the structurally strong relationship between the adjustable sections of the assemblies. As more particularly illustrated in Figs. 2 and 3, each assembly 11 comprises a pair of adjustable sheet metal panel sections 12 and 13 having such interfitting shapes as will afford the dual advantages of structural strength and rigidity, while maintaining the inner and upper section 12 in guided relation with the outer and lower section 13. Preferably, though typically such reinforced and guided relation of the sections is effected by deforming panel 13 to provide throughout its length vertically extending ribs 14 of substantially V-shaped cross section and forming channels which slidably receive the correspondingly shaped ribs 15 on the inner panel section 12. The outer edges 151 of section 13 are inwardly curved about the correspondingly turned and curved outer edges 16 of the inner section 12, so that the two sections are confined against relative lateral movement as well as separation.

The end assemblies 11 are supported by legs 17 having upper vertical portions 17a received and retained within the curved flanges 151 of section 13, the legs being interconnected by a brace 18 welded or otherwise secured to both the panel 13 and legs.

Sections 12 of the two end assemblies are interconnected by a longitudinal and center channel-shaped beam 19 having terminal end flanges 20 secured by fasteners 21 to the panel 12. As illustrated in Fig. 1, a supply or book compartment 24 having two or more sections 25 and 26, may be accommodated directly beneath the top 10 at one side of the channel 19, the compartment being formed by a shell 27 extending inwardly to the channel and having a center partition 28. If desired, a second and similar compartment structure may be placed at the opposite side of the channel.

45 The table top, section 12 and the channel 19 are structurally integrated by an angular bracket 29 directly underlying the top and having a flange 30 attached thereto and at 301 to the channel flanges, the bracket being extended transversely 50 of the table to support the top substantially across its width. The bracket has a pair of outer depending flanges 31 tapering upwardly toward the bracket extremities and attached by fasteners 32 to the outside of the panel 12. The bracket also 55 has a central depending flange 33 attached by

fasteners 34 to panel 12 at its outside, this flange being spaced at 331 from flanges 31 to accommodate the panel ribs 15.

Being supported on flanges 30 of the end brackets 29, the under surface of the table top between the flanges is elevated above the channel flanges 22. To give the intermediate extent of the table top, support on the channel, I may attach to the channel transverse members 23 corresponding in thickness to the bracket flanges 30.

Referring to Fig. 3, the panel sections 12 and 13 contain correspondingly spaced and aligned openings 35 for reception of fasteners 36 by which the upper section 12, and therefore the table top, may be retained in any position of adjustment relative to the lower section 13. Accordingly, as at such time as it may be desirable to make adjustments of the table height, it is only required that the table top and connected panels 12 be given the proper elevation, following which the insertion of the fasteners 36 will secure the parts in fixed and rigid condition.

I claim:

1. A table structure comprising a top, and vertically adjustable end supporting assemblies each including a pair of vertically elongated legs and upper and lower vertically telescopic sheet metal sections extending between said legs, one section being formed to have a vertically extending rib interfitting within a vertically extending recess in the other section, the edges of said lower section being bent about said legs, a transverse bracket plate member directly underlying said top and having a depending flange attached to said upper section, a beam member extending longitudinally of the table directly beneath said top and attached to said bracket plate member, and means connecting one of said members to said top.

2. A table structure comprising a top, and vertically adjustable end supporting assemblies each including a pair of vertically elongated legs and upper and lower vertically telescopic sheet metal sections extending between said legs, one section being formed to have a vertically extending rib interfitting within a vertically extending recess in the other section, the edges of said lower section being bent about said legs, a transverse bracket plate directly underlying said top and having a depending flange attached to said upper section, a beam extending longitudinally of the table directly beneath said top and attached to said bracket plate, and means attaching said bracket plate to the top, said sections having a vertically aligned series of registerable openings for reception of a fastener to retain the upper section in different positions of adjustment.

3. A table structure comprising a top, vertically adjustable end supporting assemblies each including upper and lower vertically telescopic sheet metal sections and a pair of elongated legs carried by and extending downwardly from the lower

section, said lower section of each supporting assembly having a pair of opposite side portions bent about said legs, the upper section having a pair of opposite side portions bent to interengage with said side portions of the lower section and guide the sections for vertical telescopic movement, said bent side portions of one section extending about the bent side portions of the other section far enough to retain the sections against horizontal separation, and means connecting the upper section of each supporting assembly to said top.

4. A table structure comprising a top, vertically adjustable end supporting assemblies each including upper and lower vertically telescopic sheet metal sections and a pair of elongated legs carried by and extending downwardly from the lower section, said lower section of each supporting assembly having a pair of opposite lateral edge portions bent about said legs, the upper section having a pair of opposite lateral edge portions bent substantially in correspondence with said lateral edge portions of the lower section to interengage therewith and guide the sections for vertical telescopic movement, said bent lateral edge portions of one section extending about the bent lateral edge portions of the other section far enough to retain the sections against horizontal separation, and means connecting the upper section of each supporting assembly to said top, one of said sections having a plurality of vertically aligned openings selectively registerable with an opening in the other section for reception of a fastener to retain the upper section in different positions of adjustment.
